(57) CLAIM

The ornamental design for an eating utensil, as shown.

DESCRIPTION

FIG. 1 is a perspective of an eating utensil;

FIG. 2 is a top plan view of an eating utensil;

FIG. 3 is a right side elevation view of an eating utensil;

FIG. 4 is a bottom plan view of an eating utensil;

FIG. 5 is a left side elevation view of an eating utensil;

FIG. 6 is a front-end elevational view of an eating utensil; and,

FIG. 7 is a back-end elevational view of an eating utensil. The broken line showing of indicia is for illustrative purposes only and forms no part of the claimed design.
